EUGENE CLAUDE, OF SOMONAUK, ILLINOIS, ASSIGNOR TO SANDWICH MANUFACTURING CO., OF SANDWICH, ILLINOIS, A CORPORATION OF ILLINOIS.

CORN-SHELLER.

1,099,339.

Specification of Letters Patent.

Patented June 9, 1914.

Application filed February 9, 1914. Serial No. 817,558.

To all whom it may concern:

Be it known that I, EUGENE CLAUDE, a citizen of the United States, and resident of Somonauk, county of Dekab, and State of Illinois, have invented certain new and useful Improvements in Corn-Shellers, of which the following is a specification, and which are illustrated in the accompanying drawings, forming a part thereof.

10 The invention relates to corn shellers of the type shown in the Patent No. 998,417, granted to Plin C. Southwick, July 18, 1911.

15 The object of the invention is to provide improved means for controlling the discharge of cobs from the shelling chamber and an embodiment of it is hereinafter described and is illustrated in the accompanying drawings, in which—

Figure 1 is a detail plan view of a corn 20 sheller, some of the parts being broken away; Fig. 2 is a detail section on the line 2—2 of Fig. 1, and Fig. 3 is a detail section on the line 3—3 of Fig. 2.

A portion of the body of the sheller is 25 represented at 10. The discharge end of the cylinder is indicated at 11 and the cylinder barrel at 12. As in the machine shown in the Southwick patent there is an upright extension, 13, of the shelling chamber adjacent its discharge end. A cob discharge 30 opening is at the end of this extension and is normally closed by means of a damper 15 hinged at its upper edge to the extension 13, or more properly to a hood 16 projecting from the end of this extension. A pivot rod 35 17 of the damper 15 is journaled in the side walls of the hood 16, and to it there is fixed a laterally projecting arm 18 carrying a movable weight 19. This weight may take 40 the form of a roller, preferably channeled to fit between top and bottom bars 20 and 21 of the arm 18.

The damper 15 and arm 18 are so related 45 that when the former is closed the latter is inclined downward toward its free end. As the damper opens, responsive to the pressure of the cobs seeking exit, the arm 18 is raised and as soon as its free end passes above the horizontal, the weight 19 tends to 50 move inwardly toward the pivot 17 and this

movement occurs as soon as the elevation becomes sufficient for gravity to overcome the frictional resistance. Preferably the roller fits freely between the top and bottom members of the arm 18 so that there is but little 55 resistance to its movement.

In machines of this type it is desirable that there be some impediment to the free discharge of the cobs and the damper is provided for this purpose. When in a vertical 60 position the damper does not sufficiently retard the cobs unless weighted. When the weight is applied directly to the damper, as in the Southwick patent, it becomes increasingly effective as it swings away from the 65 vertical position and tends to impose too great an obstacle to the movement of the cobs. By the construction herein shown and described this tendency of the weight to increase with its outward movement is obviated automatically by the inward movement of the roller 19. Should the discharge 70 of cobs decrease in volume and thus permit the damper to close, the roller immediately returns to the outer end of the arm. By this 75 construction, the parts being properly proportioned, there is provided a substantially uniform resistance to the discharge and the action of the machine is thereby substantially improved.

I claim as my invention,—

1. In a corn sheller, in combination, a shelling chamber having a cob discharge port, an outwardly opening damper covering the port yieldable to the pressure of the 85 material, and means for resisting the opening movement, such resistance being arranged to decrease as the damper moves outward.

2. In a corn sheller, in combination, a shelling chamber having a cob discharge port, means for yieldingly opposing the discharge of material through the port, the opposing force of such resisting means decreasing as the quantity of material increases.

3. In a corn sheller, in combination, a shelling chamber having a cob discharge port, an outwardly swinging damper covering the port, an arm projecting laterally from the pivotal axis of the damper and be-

ing downwardly inclined when the damper is closed, and a freely movable weight carried by the arm.

4. In a corn sheller, in combination, a shelling chamber having a cob discharge port, an outwardly swinging damper covering the port, an arm projecting laterally from the pivotal axis of the damper and be-

ing downwardly inclined when the damper is closed, and a weight in the form of a roller 10 loosely running on the arm.

EUGENE CLAUDE.
